(No Model.)

A. H. OVERMAN.
BRAKE FOR VÉLOCIPÉDES.

No. 406,462.

Patented July 9, 1889.

Albert H. Overman.

By George D. Seymour.

Atty.

UNITED STATES PATENT OFFICE.

ALBERT H. OVERMAN, OF NEWTON, ASSIGNOR TO THE OVERMAN WHEEL COMPANY, OF BOSTON, MASSACHUSETTS.

BRAKE FOR VELOCIPEDES.

SPECIFICATION forming part of Letters Patent No. 406,462, dated July 9, 1889.

Application filed May 17, 1889. Serial No. 311,172. (No model.)

To all whom it may concern:

Be it known that I, ALBERT H. OVERMAN, residing at Newton, in the county of Suffolk and State of Massachusetts, have invented 5 certain new and useful Improvements in Velocipede-Brakes; and I do declare the following to be a full, clear, and exact description of the same, reference being had to the accompanying drawings, which form a part of 10 this specification.

My invention relates to an improvement in velocipedes, the object being to produce a brake of simple, durable, and reliable construction, which will not rattle when in use.

15 With these ends in view my invention consists in certain details of construction and combinations of parts, as will be hereinafter described, and pointed out in the claims.

In the accompanying drawings, Figure 1 is 20 a broken view, in perspective, showing the application of my invention to a front-steering rear-driving bicycle. Fig. 2 is an enlarged sectional view showing the shoulder and seat which form a point of purchase for the spring; 25 and Fig. 3 is an enlarged plan view showing the spring and the brake-spoon.

As herein shown, the brake-spoon A is suspended in a virtually vertical position upon a pivot B, located just within the forward end 30 of the fork C, which carries the rear driving-wheel of the machine. The upper end of the said brake-spoon is provided with a cross-bar D, the opposite ends whereof are respectively connected with the lower ends of two light 35 connecting rods or wires E E, having their upper ends respectively connected with the opposite ends of a similar cross-bar F, located at the upper end of the upright arm of a bell-crank lever G, pivoted between lugs H H, projecting forward from the sleeve I, through 40 which the steering-rod J passes. The horizontal arm of the lever G is flexibly connected with the lower end of a two-part adjusting-rod, composed of parts K and L, clamped together by a screw M and having its upper 45 end connected with the inner end of the curved hand-lever N pivoted in a clip O, secured to the handle-bar P and provided with a hand-piece Q, located in front of the adjustment handle R of the said bar. The said 50 brake-spoon, connecting-rods, bell-crank le-

ver, adjusting-rod, and hand-lever constitute a series of levers or connected brake parts, forming a brake-train. A spring consisting of ends S S, coils T T, and a loop U, is combined with the frame of the vehicle, so as to press upon the upper end of the brake-spoon with the effect of constantly pushing the said end of the spoon rearward. This action of the spring is transmitted through the brake-train, and operates to press a shoulder V, formed in the hand-lever, against the handle-bar, which forms a seat for it, as at W, as shown by Fig. 2 of the drawings, the said shoulder and seat forming a point of purchase 65 from which the spring operates in keeping the train under tension. As the spring, and hence the train, is constantly under tension, the slack or play in the train is always taken up, whereby the train can never rattle, thus 70 avoiding annoyance and wear. The amount of tension so secured may be regulated by adjusting the adjusting-rod to lengthen or shorten it. To set the brake, the shoulder referred to is pressed against its seat and the 75 adjusting-rod lengthened until the spring is under sufficient tension to normally hold the shoulder against the seat under all ordinary conditions of use.

It is apparent that I am not limited in practicing my invention to the system of levers shown and described, for one or more levers, however constructed or arranged, having a spring at one end and a stop or seat at the other end may fulfill the purposes of my invention. I would therefore have it understood that I do not limit myself to the exact construction shown and described, but hold myself at liberty to make such changes and alterations as fairly fall within the spirit and 85 scope of my invention.

Having fully described my invention, what I claim as new, and desire to secure by Letters Patent, is—

1. In a velocipede, the combination, with a 95 brake composed of one or more levers, of a spring located at one end of such lever or levers, and a seat located at the other end thereof and forming a point of purchase for the spring for holding the lever or levers 100 against rattling, substantially as set forth.
2. In a velocipede, the combination, with a

brake-train consisting of connected series of brake parts, of a spring located at one end of the train and a seat located at the other end thereof and forming a point of purchase for the spring for holding the train under tension and against rattling, substantially as set forth.

3. In a velocipede, the combination, with a longitudinally-adjustable brake-train consisting of a connected series of brake parts, of a spring located at one end of the train and a seat located at the other end thereof and forming a point of purchase for the spring in holding the train under tension and against rattling, substantially as set forth.

4. In a rear-driving front-steering bicycle, the combination, with a brake-spoon placed for engagement with the driving-wheel, con-

necting-rods, a bell-crank lever, an adjusting-rod, and a hand-lever, the said parts being connected to form a brake-train, of a spring 20 pressing against the spoon, and a shoulder formed upon the hand-lever and pressing against the handle-bar, which forms a point of purchase for the spring which holds the train under tension and against rattling, substantially as set forth.

In testimony whereof I have signed this specification in the presence of two subscribing witnesses.

ALBERT H. OVERMAN.

Witnesses.
